REINFORCED WRIST WATCH BAND

Bernard G. Pedersen, San Francisco, Calif.

Application December 4, 1947, Serial No. 789,660

1 Claim. (Cl. 224—4)

1 My invention relates to wrist watch bands and more particularly to bands or straps which are made of textile fabric, leather, or plastic material, and which include reinforcing means whereby to prevent loss of the watch through failure of the band material.

As is well known, wrist watch bands or straps are frequently made of leather, textile fabric, or plastic material, and that, moreover, leather and textile fabric bands frequently fail by virtue of the rotting of the strap which results from the intermittent soaking and drying in perspiration from the wearer's wrist. Frequently, such rotting goes unnoticed, or at least the extent of it is not realized until the strap breaks and the watch falls off of the wearer's wrist and is lost or damaged.

With the foregoing in view, an object of my invention is to provide an improved reinforced wrist watch band or strap.

A further object is to provide an improved reinforced wrist watch band or strap which includes reinforcing wires extending longitudinally of the strap, and which wires are substantially non-resilient whereby to readily conform to the contours of the wearer's wrist.

A further object is to provide an improved wrist watch strap which is reinforced by substantially non-resilient wires and wherein one end of at least one wire is fixedly attached to a metallic sleeve which is adapted to be connected to a wrist watch.

A further object is to provide in a wrist watch strap such as that last described wherein said sleeve is adapted to detachably receive the pintles of a wrist watch for detachably connecting the strap to the watch.

A further object is to provide an improved reinforced wrist watch strap which is reinforced by substantially non-resilient wires extending longitudinally of the strap, which wires are fixedly attached at one end to a metallic sleeve, and which sleeve incorporates therein a pair of oppositely directed spring loaded pintle pins for detachably connecting the strap to a wrist watch.

Other objects and advantages reside in the particular structure of the invention, combination and arrangement of the several parts thereof, and will be readily understood by those skilled in the art upon reference to the attached drawing in connection with the following specification, wherein the invention is shown, described and claimed.

In the drawing, Fig. 1 is a plan view of a reinforced strap according to the invention, an upper ply of one strap section being separated

from the lower ply and turned back to show the arrangement of the reinforcing material;

Fig. 2 is a view like Fig. 1, showing the reinforcing material apart from the strap providing material;

Fig. 3 is an enlarged view with parts broken away of one of the sections shown in Fig. 2;

Fig. 4 is a transverse vertical section taken substantially on the plane of the line 4—4 of Fig. 3;

Fig. 5 is a bottom plan view of a wrist watch showing the strap sections fragmentarily, one of said sections being shown in longitudinal vertical section and disclosing a modified form of the invention;

Fig. 6 is a longitudinal vertical section with parts broken away and taken substantially on the plane of the line 6—6 of Fig. 1.

In the drawing, and referring more specifically to the form of invention shown in Figs. 1, 2, 3, 4 and 6, the strap according to this form of the invention comprises a pair of strap sections 6 and 12. The strap section 6 comprises a tongue section composed of a pair of plies 7 and 8 formed of a strip of any suitable strap providing material, which is doubled on itself to provide the bight 9 in which is secured in any suitable manner a sleeve 10. The sleeve 10 extends transversely of the plies 7 and 8, as shown. At this time, it should be pointed out that although the sleeve 10 is preferably formed of metallic material, it is obvious that it could in some instances be formed of plastic, or the like. A reinforcing wire A is interposed between the plies 7 and 8 of the tongue section 6, and is U-shaped to provide parallel legs connected together at one end by a flat loop 40 conforming substantially to the shape of the free end 41 of the tongue section 6. Free ends A' of the wire A are transversely directed and secured to the sleeve 10 in any suitable manner, as by being soldered or brazed thereto.

The buckle section 12 of the strap likewise comprises a two-ply arrangement of a strip of any suitable strap material, one end of which is doubled to provide a bight 14 and also overlaps the other end, Fig. 6. The bight 14 is bifurcated and looped about a pair of laterally spaced minor sleeves 13a. Minor sleeves 13a are pivoted on a shaft or cross bar 43 of any suitable buckle 13.

The tongue 42 of the buckle is pivoted on the shaft 43 and is interposed between the minor sleeves 13a and the bifurcations of the bight 14 of the strap material. The other end of the buckle providing strap section 12 is looped to provide a bight 17 which is secured in any suitable manner to a sleeve 22 which corresponds to the sleeve 10.

in the tongue providing section 6. The under-layer of the strap material of buckle section 12 extends substantially to the buckle 13 and is secured to the free end of the upper layer by suitable stitching 20. Suitable looped keepers 19 are secured on the buckle section 12 in any usual manner, as by having loops thereof interposed between the plies. Such keepers are secured in place against longitudinal movement by lines of stitching 18 and 21.

The lines of stitching 18 and 21 extend longitudinally of the tongue and buckle sections 6 and 12, respectively, outwardly of the reinforcing wires A and B whereby to secure the plies of the tongue and buckle sections together in a well known manner. Such wires B extend longitudinally of the buckle section 12 and the ends B' are securely fastened to the sleeve 22 in any suitable manner, as by being soldered thereto. The opposite ends of the wires B are securely fastened, as by being soldered, to said pair of minor sleeves 13a, each of which is pivoted on the shaft of the buckle 13, as aforesaid.

Holes 44 for the buckle tongue 42 are formed through both plies 7 and 8 intermediate the parallel portions of the wire B.

Referring now to the form of invention disclosed in Fig. 5, a wrist watch 30 is provided with the usual laterally extending ears 31 each of which are formed with aligned apertures 32 for the reception of the usual pintle pins. In this form of the invention, the strap sections 33 and 37 conform in structure substantially to the structure of the strap sections previously described with the exception that the reinforcing wires A and B are secured to sleeves 34 each of which contains an expansive coil spring 35. The outer ends of each of the springs 35 bear against the inner ends of a pair of oppositely disposed pintle pins 36. The free or outer ends of the pins 36 extend outwardly of the sleeves 34, and upon depression of such pins against the action of the spring 35, permit the pins to be engaged in the apertures 32 in the ears 31 of the wrist watch. Thus, this form of the invention differs from that previously described in that the sleeves 34 themselves comprise the pintles for the watch. Sleeves 34 are rigidly secured as by soldering to the reinforcing wires A and B. Hence, the pintles and strap sections are substantially integral.

It is obvious from the foregoing that by virtue of the fact that the reinforcing wires are fixedly secured both to the buckle and to the reinforcing sleeves 10, 22, or 34, that the entire watch is actually supported by the reinforcing wires A and B. Thus, there is no substantial strain on the material or sheath providing the strap material for the strap section 6 and 12. Consequently, such material may be very light weight and

may comprise substantially delicate material. By forming the wires of highly flexible, non-resilient material, they bend readily to conform to the wrist shape and pass freely through the buckle 13 or like fastener.

While I have shown and described what is now thought to be the preferred embodiments of the invention, it is to be understood that the same is susceptible of other forms and expressions. Consequently, I do not limit myself to the precise structures shown and described except as hereinafter claimed, it being understood, of course, that the term "wire" as used herein is to be construed and comprehending any flexible equivalent thereof such as cord, metal or metal substitute.

I claim:

In a wrist watch strap, the combination with a pair of two ply strap sections, one of said sections having a buckle on one end, the other of said sections having a tongue formed on one end, both of said sections being formed with transversely extending bights on the ends opposite to said tongue and buckle; of a metallic sleeve in each bight, spaced metallic sleeves engaging the rear cross bar of the buckle, a pair of flexible non-resilient reinforcing strands of wear-resisting material and incorporated in each section between the plies thereof, said strands being laterally spaced and extending longitudinally substantially the entire length of each section, an end of each strand in each section being connected to one of said sleeves and the free ends of each strand section within the buckle-carrying portion connected rigidly to each of the buckle-engaging sleeves, whereby the opposite end of each strand in said buckle section is pivotally secured to said buckle by the spaced metallic sleeves and the opposite ends of said strands in said tongue section being merged to provide a bight in the region of the tongue end.
